UNITED STATES PATENT OFFICE.

GEORGE GODDU, OF WINCHESTER, MASSACHUSETTS, ASSIGNOR TO UNITED SHOE MACHINERY CORPORATION, OF PATERSON, NEW JERSEY, A CORPORATION OF NEW JERSEY.

FINISHING MACHINE.

Application filed November 13, 1922. Serial No. 600,491.

This invention relates to finishing machines and is herein shown as embodied in a machine for burnishing the edges of heels of boots and shoes.

5 Machines for performing finishing operations on heels usually employ rotary tools which have their contours shaped to fit the particular heels to be burnished. The heels of shoes of different styles, particularly 10 those for women's shoes, differ greatly in height and form and some are very abruptly curved while other styles have an almost flat periphery. As a consequence many different tools have been required properly 15 to finish all these styles and shapes.

Accordingly, an object of this invention is to provide an improved tool which is adapted for finishing a variety of heels having widely differing shapes or degrees of curvature. In the illustrated machine, in accordance with an important feature of the invention, this object is attained by providing one set of individual burnishing elements adapted to treat all shapes of heels, different 20 templets being inserted in the tool axis to change the configuration of the tool as a whole so that the contour of the burnishing surface will correspond to the heels. As shown, the tool comprises a holder, a series 25 of individual rubbing elements pivoted to the holder, and a templet engaging the pivotally mounted elements and constructed and arranged to cause the tool as a whole to conform to a contour determined by said 30 templet. Thus one set of burnishing elements suffices for many different shapes of heels and the precise contour desired is produced by selecting a templet of the necessary 35 shape to control the relative positions of said burnishing elements. On account 40 of minor irregularities in the work, it is desirable that the burnishing surface be slightly yieldable to search out and find these irregularities. In accordance with a 45 further feature of the invention, the illustrated burnishing elements, while conforming as a whole to the desired contour, have lost motion connections with the controlling templets so that they can be moved inwardly 50 by pressure of the work against the action of centrifugal force. In view of the varying heights of heels, it is also desirable to vary the length of the burnishing surface to correspond. Accordingly, another fea-

ture of the invention consists in provision 55 for decreasing the burnishing surface to just what is needed to treat any given heel. In the illustrated machine this is accomplished by forming and arranging the templets, or some of them, to withdraw a pre- 60 determined number of the burnishing elements from operative position at one end of the tool, the number of burnishing elements so withdrawn in a given instance depending upon the contour of the particular heel to 65 be treated. Preferably the templets are adjustably held within the tool so that any one templet, by occupying different positions in the same tool, is capable of varying the predetermined number of elements in ac- 70 tivation and so varying the extent of the active surface. Furthermore, this variation may occur during operation of the tool.

The invention provides also, as a further feature, novel means for heating the tool, 75 which is constructed and arranged to maintain the heating element in heat conducting relation to the tool as the latter rotates and oscillates along its axis of rotation.

Other features and advantages of the in- 80 vention will appear from a consideration of the detail specification considered with the accompanying drawings in which,

Fig. 1 is a front elevation of a portion of a burnishing machine provided with the 85 improved tool;

Fig. 2 is a perspective view of a detail; Fig. 3 is a plan view of the tool, partly in longitudinal section;

Fig. 4 is a section transversely of the tool 90 axis;

Fig. 5 is a view of one of the templets;

Fig. 6 is a view similar to Fig. 3 of a somewhat modified form of tool holder; and

Fig. 7 is an exploded detail view of parts shown in Fig. 6.

The burnishing tool is mounted near the end of a shaft 8 journaled in a frame 10 and driven through spiral gears from a vertical drive shaft 12. Slight axial movement of the tool is desired to cause the burnishing action of the individual elements to overlap. This is accomplished by a cam 14 fixed to the shaft 8 and having a groove 100 engaging a roller 16 rotatable on a pivot 105 fixed to the frame.

The tool is indicated generally at 18 and

comprises a series of individual work engaging elements arranged in series both longitudinally of the tool axis and circumferentially thereof. The holder for the elements is constructed as follows:—Secured to the shaft 10 by a set screw 20 is a hub 22 having a circular flange 24 to which is secured a plurality of rods 26 extending parallel to the tool axis and arranged in a circular series. The rods are threaded, as indicated at 28, in the flange 24 and have bracing collars 30 resting in recesses of the flange. A second hub 32 has an annular flange 34 carrying a series of hollow rods 36 parallel to the tool axis and arranged in a circular series corresponding to the rods 26, the hollow rods 36 being designed to slip over the rods 26. Each rod 36 is threaded as indicated at 38 in the flange 34 and has a bracing collar 40 fitting in a recess of the flange. Burnishing elements are sleeved on the hollow rods for pivotal movement and held loosely in place by nuts 42 upon the ends of the hollow rods. The hub 32, flange 34, hollow rods and burnishing elements are detachable as a unit from the rods 26 if it is desired to replace the burnishing elements with others of a different kind or of a different width.

A series of work engaging elements, herein shown as burnishing elements 50 and 52, are pivoted on each of the hollow rods. The burnishing elements are in the form of curved levers each having a radially extending arm 54 which is rounded and received loosely in one of a series of cam grooves 56 extending along the surface of a cylindrical templet 58. The templet 58 is representative of one of a set of interchangeable templets each designed to control the contour of the tool for a particular heel, acting to vary the diameters of the burnishing surfaces of the respective series of elements which lie side by side in parallel planes. The templet is inserted within the axis of the tool and is held on the expandable end of the shaft 10 by a screw 60 having a conical surface. The templet is held from rotation relatively to the tool by a pin 62 projecting into a slot in the hub 32 and this pin also insures the positioning of the cam grooves in the proper relation to the burnishing elements. The hub 32 and associated detachable parts are held on the templet by a set screw 64. A tread rest 66 is adjustable along the tool, being carried by a bar 67 slidable on the frame and capable of being clamped in position by a hand screw 68.

The burnishing elements 50 and 52 are curved in spiral fashion from their pivots and extend to a point which is approximately 90° from the pivots as seen from the tool axis. Consequently any movement of these elements will cause their working surfaces to move in or out with respect to the tool axis and thus change its diameter or contour. The lost motion provided by the loose connection of the arms 54 with the cam grooves 56 allows the burnishing elements to be pressed inwardly by the work against the action of centrifugal force. These elements are standardized in one or more lengths to facilitate economical production and, where two lengths are provided, they are arranged as shown with the longer and shorter arms 52 and 50 alternating. Thus the elements 52 will lag behind the elements 50 and thereby distribute the blows on the surface of the work and equalize the resistance. Wax is better distributed also. If the tool is used for burnishing it is preferably rotated clockwise as seen in Fig. 4 but for other purposes it may be driven in the other direction. With each tool, it is intended to use a series of templets each having its cam grooves shaped in a manner determined by the particular heel to be burnished. Since the radially extending arms 54 are shorter than the work engaging arms, the curvature of the grooves 56 may be made much flatter for a given tool contour and the templet can be made small so that it will easily enter the tool axis.

The tool is heated at both ends by electrically heated plates which are yieldably mounted to accommodate the oscillation of the tool. One heated plate 69, having sockets to receive heating units, bears against the flange 24. It is supported by pins 70 slidably mounted in the frame, there being springs 72 around the rods to hold the plate and flange in yielding engagement. A bracket 74 fixed to the frame supports a pair of guide pins 76 for a heating plate 78 having sockets for electric heating units. The plate is pressed against the flange 34 by coil springs 80 surrounding the guide pins. These electric units are arranged to maintain said plates 69 and 78 at temperatures higher than that of the tool so that heat will be transferred to the tool by conduction. Any suitable wax applying and spreading mechanism indicated generally at 82 may be employed.

In Figs. 6 and 7 there is shown a slightly modified form of tool holder in which the parts corresponding to the other figures have the same reference numerals with an additional 100. The hub 122 has a flange 124 to which is secured a series of rods 126 threaded as at 128 in the flange and having a bracing collar 130. A ring 134 receives the ends of the rods which are secured in place by nuts 135. A templet 158 having cam grooves 156 of any desired contour is inserted within the axis of the tool and positioned by a lug 162 on the flange 124 entering one of the grooves. The templet shown is adapted 130

to adjust the tool for burnishing a low straight heel having a rubber top lift. The templet, as appears in Fig. 7, has the inner portions of the grooves 156 formed to draw all the burnishing elements out of action except those at the left which are of sufficient combined width to cover the particular part of the heel to be treated. In the form shown in Figs. 3 and 5, the templet is so formed as to withdraw three of the burnishing elements from working position and hold the rest in a position that will produce the contour desired for an excessively curved heel. It is expected that one form of tool will take care of all ordinary shapes of heels, but if the tool is to be used only on French heels or the like, it is preferable to back off or slant as at 53 (Fig. 3) those burnishing elements which would lie against the abrupt curve near the tread of such heels, thereby distributing the pressure over a greater area.

Preferably the templets are provided with mechanism for moving them endwise to select a sufficient number of burnishing elements to cover the heel and to draw the others out of action. Furthermore, the templets can be moved during the operation of the tool as when operating on a heel the height of which varies at the rear and front. Each templet has a groove 88 near its outer end engageable with pins extending from a bifurcated arm 90 (Fig. 6) on a hand lever 92 pivoted at 94 to the frame. The hand lever carries a hand screw 96 extending through an arcuate slot 98 in a fixed bracket to hold the templet against axial movement when desired. When operating on the heel shown in Fig. 6, for example, the templet is locked. On the other hand, with a heel such as shown in Fig. 3 which is lower at the front than at the rear, the hand lever 92 can be swung to slide the templet and increase or diminish the number of burnishing elements in action as the heel is turned. The effective length of the tool is thereby changed and although the surface contour, as determined by the templet, remains the same, its position is shifted along the tool. Although the tool herein illustrated by way of example is a burnishing tool for heels, it is apparent that the invention in its broader aspects is not limited to burnishing nor to operating on heels.

Having thus described my invention, what I claim as new and desire to secure by Letters Patent of the United States is:—

1. In a machine of the character described, a finishing tool comprising a pivotally mounted holder, a series of individual work engaging elements arranged on said holder side by side in an axial direction, each of said elements being mounted on the holder for independent movement, and a templet

for controlling the deflection of said elements from the axis of the holder to cause the tool as a whole to conform to a predetermined contour. 65

2. In a machine of the character described, a finishing tool comprising a holder having a series of individual work engaging elements each movably mounted on the holder for independent control, a templet for controlling said elements to cause the tool as a whole to conform to a predetermined contour, and lost motion connections between said templet and said elements to allow limited movement of said elements for the purpose set forth. 70 75

3. In a machine of the character described, a burnishing tool comprising a holder, a series of individual rubbing elements, each pivotally mounted on the holder, and means for adjusting said elements around their pivots to cause the tool as a whole to conform to a desired contour. 80 85

4. In a machine of the character described, a finishing tool comprising a pivotally mounted holder, a series of work engaging elements each pivotally mounted on the holder upon axes substantially parallel to the axis of the holder, and a templet engaging said pivotally mounted elements and constructed and arranged to change the configuration of the tool as a whole to cause it 90 95 to conform to a contour determined by said templet.

5. In a machine of the character described, a finishing tool comprising a holder, a series of work engaging elements, each 100 pivotally mounted on the holder and having a controlling arm, and a templet engaging the controlling arms and constructed and arranged to cause the tool as a whole to conform to a desired contour. 105

6. In a machine of the character described, a burnishing tool comprising a holder, a series of rubbing elements, each pivotally mounted on the holder and having an arm extending towards the tool axis, and a templet engaging the arms and having a predetermined relation to the contour of the work to cause the elements generally to assume said contour, said engagement of the templet with the arms having provision for lost motion to allow said rubbing elements to swing in and out to find the minor irregularities in the work. 110 115

7. In a machine of the character described, a burnishing tool having a circumferential series of burnishing elements, and a templet for adjusting said elements toward or from the tool axis to expand or contract the circumference of the burnishing surface. 120

8. In a machine of the character described, a burnishing tool comprising a holder having a series of supports arranged in a circular series, a rubbing element movably

- 4 mounted on each support, said elements collectively forming a circumferential burnishing surface, and means for engaging and moving said elements on the supports to 5 expand or contract the circumference of said circumferential surface. 65
9. In a machine of the character described, a burnishing tool comprising a holder having parallel pivot rods arranged in a 10 circular series, a rubbing element pivotally mounted on each rod, said elements collectively forming a circumferential burnishing surface, and means for swinging said elements on the rods to expand or contract said 15 surface. 70
10. In a machine of the character described, a rotary burnishing tool comprising a holder and a series of burnishing elements, each pivotally mounted on the holder on 20 axes substantially parallel to the longitudinal axis of the tool, said elements curving outwardly in spiral fashion from said tool axis. 80
11. In a machine of the character described, a rotary tool comprising a holder and a series of work engaging elements, each pivotally mounted on the holder, said elements curving outwardly in spiral fashion 25 from the tool axis to form a circumferential working surface, and means for adjusting the positions of said elements on their pivots to change the radius of said surface. 90
12. In a machine of the character described, a burnishing tool comprising individual rubbing elements arranged in series 30 both longitudinally and circumferentially of the tool axis, and a templet for adjusting the rubbing elements toward or from the tool axis. 95
13. In a machine of the character described, a burnishing tool comprising a holder having a series of parallel rods and a series of curved rubbing arms pivotally mounted on each of said rods with the arms 35 on adjacent rods arranged in overlapping relation. 100
14. In a machine of the character described, a rotary tool comprising a holder having a series of supporting rods, a series 40 of work engaging elements movably mounted on each of said rods, and means for causing each series of elements to conform to any predetermined contour. 105
15. In a machine of the character described, a hollow burnishing tool comprising a holder having a circular series of supporting rods, rubbing elements movably mounted on said rods, and a cylindrical templet extending through the tool axis 45 and engaging said rubbing elements. 110
16. In a machine of the character described, a hollow burnishing tool comprising a holder having a circular series of supporting rods, rubbing elements pivotally 50 mounted on said rods and having radial projections, and a cylindrical templet extending through said tool and having cam grooves for engaging said projections to control the position of the elements. 115
17. In a machine of the character described, a rotary tool having series of independently mounted work engaging elements arranged in parallel planes, and a templet for varying the diameters of the series of elements in the respective planes 55 to determine the contour of said tool. 75
18. In a machine of the character described, a rotary burnishing tool having a circular series of pivotally mounted work engaging burnishing elements movable towards and from the axis of the tool, and a member for simultaneously controlling all of said elements to change the diameter of the tool. 80
19. In a machine of the character described, a rotary burnishing tool having a plurality of adjustable elements rotatable about a common axis and forming a circumferential work engaging surface, and means within the axis of the tool for controlling the longitudinal contour of said surface. 85
20. In a machine of the character described, a member having a plurality of parallel rods, means for rotating said member, a second member having a plurality of hollow rods arranged to enclose the rods of the first set, and work engaging elements carried by said hollow rods. 90
21. In a machine of the character described, a burnishing tool comprising a series of individual burnishing elements, and means for holding said elements in a predetermined relation to conform approximately to the curve of a heel, those elements at the more sharply curved part of the heel being slanted or backed off to avoid marking the heel. 100
22. In a machine of the character described, a burnishing tool comprising a holder having a circular series of supporting rods, and rubbing elements of different lengths movably mounted on each of said rods, the longer and shorter elements arranged in succession along the rods. 110
23. In a machine of the character described, a burnishing tool having a series of burnishing elements rotatable about a common axis, means for rotating the tool, and means for oscillating the tool in the line 115 of its axis to cause the burnishing action of one element to overlap that of the next. 120
24. In a machine of the character described, a burnishing tool having a plurality of burnishing elements in parallel planes, the burnishing elements in one plane arranged to lag behind the elements in the next plane, means for rotating the tool, and 125

means for oscillating the tool to cause the action of adjacent elements to overlap.

25. In a machine of the character described, a rotary tool having a series of individual work engaging elements, certain of said elements being mounted for movement from operative to inoperative position, and a templet for changing the length of the tool by withdrawing some of said elements from operative position.

26. In a machine of the character described, a rotary tool having a series of individual work engaging elements movable towards and from the axis of the tool, a templet for controlling the positions of said elements to determine the contour of said tool, and means for moving the templet during the rotation of the tool to change the operative length of the tool.

27. In a machine of the character described, a rotary tool having circular series of work engaging elements, each movable towards and from the axis of the tool, and means for moving some of said series of elements toward the axis of the tool to reduce the operative length of the tool.

28. In a machine of the character described, a rotary tool having a series of work engaging elements movable towards and from the axis of the tool, means for controlling the positions of said elements to determine the surface contour of said tool, and means for causing said surface contour

to shift its position along the tool during the rotation of the tool.

29. In a machine of the character described, a burnishing tool having a yieldable peripheral surface, and means for contracting or expanding the circumference of some portions of said surface to vary the contour of the tool as a whole.

30. In a machine of the character described, a rotary tool mounted for oscillation along its axis of rotation, a heated member having a temperature higher than that of the tool, and means for supporting said heated member for movement parallel to the axis of rotation to maintain it in heat conducting contact with said tool as the latter rotates and oscillates.

31. In a machine of the character described, a rotary tool, means for rotating said tool and oscillating it along its axis of rotation, a heated plate constructed and arranged to transfer heat to said tool, means for supporting said plate slidably for movement in an axial direction, and resilient means to hold it in contact with a surface of said tool normal to the axis thereof in order that the plate may be maintained in heat conducting relation to the tool as the latter rotates and oscillates.

In testimony whereof I have signed my name to this specification.

GEORGE GODDU.
